SHIELDED ROLLER PAINTING DEVICE

Angelo J. Brunelli, Niles, and Samuel J. Mortaro,
Youngstown, Ohio

Application September 13, 1954, Serial No. 455,704

6 Claims. (Cl. 15—248)

This invention relates to a roller painting device for transferring paint and like material to a surface to be painted and more particularly to a surface to be painted adjacent a door frame, window casing, wall or ceiling corner and the like.

The principal object of the invention is the provision of a roller painting device incorporating a guarding and guiding element enabling the roller painting device to apply coating material to a predetermined area.

A further object of the invention is the provision of a roller painting device incorporating a guarding and guiding element movably disposed with respect to the paint applying surface of the device to enable the same to be used on the right hand and left hand sides of an object defining an edge line with respect to the paint being applied.

A still further object of the invention is the provision of a roller painting device constructed in a novel manner incorporating a guard element hingedly affixed thereto and acting to guide and guard the roller painting device with respect to a desired area to be painted and permitting the roller painting device to apply coating material from the complete peripheral surface thereof.

A still further object of the invention is the provision of a roller painting device which may be used for applying coating material to a wall surface immediately adjacent a door frame, window casing or the like without applying any of the coating material to the door frame or door casing and enabling a rapid and efficient coating operation to be performed therealong.

The roller painting device disclosed herein comprises an improvement in the art relating to roller painting devices in that the rotatable member or roller is positioned on supporting arms, one of which in turn also carries a movable guiding and guarding element which may be positioned between an end of the roller and an object such as a door frame or window casing and effectively guide the roller painting device and guard the door frame and window casing or the like from the application of coating material by the roller.

Those experienced in the art will recognize that roller painting devices have been widely adopted for applying coating materials such as paints and other wall coatings and that such roller painting devices as have been heretofore developed have had a common inability to apply the coating material up to a door frame, window casing, ceiling line or the like without applying some of the coating material to the door frame, window casing or ceiling line which is objectionable.

Specialized roller painting devices have been designed for special purposes such as painting window sash and the like and wherein rotatable disc-like guards have been employed but such devices are not readily adaptable to painting a wall surface adjacent a door frame window casing or ceiling line as there is no provision for selectively positioning a disc-like guard with respect to the portion of the roller painting device contacting the wall surface.

The present invention provides a novel guiding and guarding element in the nature of a half-circular shield of a diameter larger than the diameter of the adjacent end of the roller painting device and offset with respect to the axial center thereof so that complete flexibility of positioning of the shield is possible.

Additionally, the shield is hingedly affixed to the structure supporting the roller painting device so that it may be reversed to enable the device to be used on the right or left hand side of a door or window casing or in a right or left hand operation along a ceiling line.

With the foregoing and other objects in view which will appear as the description proceeds, the invention resides in the combination and arrangement of parts and in the details of construction hereinafter described and claimed, it being the intention to cover all changes and modifications of the example of the invention herein chosen for purposes of the disclosure, which do not constitute departures from the spirit and scope of the invention.

20 The invention is illustrated in the accompanying drawing, wherein:

Figure 1 is a side elevation of the roller painting device.

Figure 2 is an end elevation of the roller painting device.

25 In the form of the invention illustrated in the drawing and as seen in Figure 1, the device of the invention comprises a handle 10 having a supporting structure 11 positioned in an end thereof and extending outwardly therefrom and including a pair of spaced arms 12—12, the outermost ends of which engage and rotatably support a rotatable member or roller 13 which is conical in shape and the outer surface of which is provided with an outer covering 14 of fabric material, the nap or hairs of which project outwardly radially from the roller 13 on all sides thereof. The covering material 14 may be woven cloth, pile fabric or other suitable material which may be used for the application of paint to a wall surface or the like.

The ends of the roller comprise a large circular end 40 15 and a smaller circular end 16 having centrally disposed openings communicating with an axial bore in the roller 13 and in which the inturned ends of the arms 12 of the handle structure 11, heretofore referred to, are journaled.

45 A half-circular shield 17 is provided with a plurality of projecting extensions 18—18 along a portion of a straight edge 19 of the shield 17. Each of the extensions 18 is curved to form a hinge structure rotatable about one of the arms 12 of the handle structure 11. As illustrated in the drawings, the extensions 18 are alternately curved in opposite directions so that a complete piano hinge-type engagement is had with respect to the arm 12 of the handle structure 11. The remainder of the half-circular shield 17 is arcuate in shape and of a diameter larger than the diameter of the large end of the roller 13 and its covering material 14, as may best be seen by referring to the end view comprising Figure 2 of the drawings.

50 In Figure 2 of the drawings the shield 17 is shown in solid lines in a position comparable with the illustration of Figure 1 and in dotted lines in its alternate position wherein it is in guiding and guarding relation to the other half of the roller 13. It will be seen that the size and shape of the shield 17 is such that approximately one quarter of the surface area of the material 14 on the roller 13 extends beyond the shield 17 while another quarter of said area lies behind the shield 17 and that this same relation of exposed and protected areas exist whether the shield 17 is in left hand position (as in solid lines in Figure 2 of the drawings) or in right hand position (as shown in dotted lines in Figure 1 of the drawings).

It will be observed that the portion of the shield 17 furthest from the straight edge 19 thereof is somewhat flattened, as indicated by the numeral 20, so that this portion of the shield 17 follows closely along the wall surface being coated when the roller painting device is being used to apply coating material to a wall immediately adjacent a door frame, window casing, ceiling line or the like.

It will also be seen that the operator can readily control the relative positioning of the shield 17, the semi-flattened area 20 thereof and the exposed peripheral surface of the covering material 14 of the roller 13 by changing the relative positioning of the handle 10 with respect to the wall surface being covered.

It will also be seen that when the device is run in a straight line as, for example, along the edge of a door frame or window casing, the conical shape of the roller will automatically position the majority of the edge of the roller away from the side of the door frame or window casing as the end 15 of the roller will be inclined at an angle with respect thereto. The shield 17 is thus operable only along the semi-flattened area 20 of its arcuate edge as concerns the immediate contact of the roller and the door frame or window casing. The shield itself lies on a spaced parallel plane with respect to the end 15 of the roller and thus enables the operator to readily see the wall surface and the adjacent edge of the door frame or window casing so that an expert job results.

The efficiency of the roller painting device is further enhanced by the fact that the conical shape of the roller requires the surface thereof contacting the wall being coated to slide sidewardly in small degree as the conical roller is moved in a straight line along a door frame or window casing rather than a curve which would result in the even rotation of the surfaces of the conical roller against the wall being coated. The resultant application of coating material such as paint is thereby expedited and a single pass of the roller painting device serves to effectively coat the desired area with no streaking or smearing of the coating material on the edge of the door frame, window casing or ceiling line being followed.

It will thus be seen that the roller painting device meets the several objects of the invention.

Having thus described our invention, what we claim is:

1. The combination of a roller painting device for applying coating material comprising a handle, a bifurcated supporting structure including an interconnecting member carried by said handle, a roller journaled for rotation on said interconnecting member and having an outside surface adapted for transferring coating material thereon to a surface over which said roller is rolled, and a shield comprising a flat member, one edge of which is of flattened arcuate shape and the other edge of which is straight, said shield hinged along its straight edge to said supporting structure alongside one end of said roller, said shield being larger than the adjacent half section of said roller and positioned in offcenter relation thereto.

2. The combination of a roller painting device for applying coating material comprising a handle, a pair of shafts projecting from said handle and extending in spaced parallel relation and having their outer ends inturned, a fabric covered conical shaped body received over the shaft ends and freely rotatable thereabout, and a shield

5 mounted on one of said parallel shafts immediately adjacent to the large end of said body, said shield having a straight edge, a hinge structure on one part of said straight edge movably securing the said shield to said shaft, said shield being substantially half-circular in shape with the circular edge thereof being of a diameter greater than the larger end of said conical shaped body and said shield mounted on said shaft with a portion of the half-circular edge thereof level with the surface of the larger end of said conical shaped body with a portion of said shield extending outwardly beyond the surface of said conical shaped body.

10 3. In a shielded roller painting device for applying coating material comprising in combination a handle, a pair of shafts connected to one end of the handle and projecting therefrom and having portions positioned in spaced parallel relation and joined at their outermost ends by a transverse section, a roller journaled for rotation on said transverse section and provided with an outer covering of pile fabric material, a shield comprising a flat half-circular member having a straight edge and a flattened arcuate edge and hinged at its straight edge to one of said parallel shaft portions adjacent one end of said roller, the area of the half-circular shield being 15 greater than the area of the adjacent half-circular end of said roller, with a portion of said arcuate edge level with the surface of said roller and another portion of said arcuate edge positioned outwardly beyond the edge of said roller.

20 4. The roller painting device set forth in claim 2 wherein the shield is formed of thin flat metal.

25 5. A shielded roller painting device for applying paint to a wall surface adjacent a door frame and the like comprising in combination a handle, a supporting structure extending from one end of said handle, a truncated conical shaped roller journaled on said supporting structure, said roller having an outer covering of paint holding material, said handle being offset with respect to the ends of said roller, said supporting structure having at least one portion thereof positioned in a spaced parallel plane with respect to the plane of the large end of said roller and adjacent thereto, a shield, one edge of which is generally arcuate and another edge of which is straight, said shield movably secured along a portion of its straight edge to 30 said portion of said supporting structure adjacent the large end of said roller, with a portion of the generally arcuate edge of said shield lying inside the peripheral edge of the roller and another portion of the generally arcuate edge of the shield lying outside the peripheral edge of the roller and acting to shield said door frame from the peripheral edge of the roller during a painting operation.

35 6. The roller painting device as set forth in claim 5 wherein the shield comprises a thin flat metal body.
